UNITED STATES PATENT OFFICE.

SVENNING DREYER, OF WOODCLIFF, NEW JERSEY, ASSIGNOR OF ONE-HALF TO JOHN PERCY GLANDER, OF RICHMOND HILL, NEW YORK.

MANUFACTURING CONFECTIONERY.

Application filed September 8, 1923. Serial No. 661,599.

To all whom it may concern:

Be it known that I, SVENNING DREYER, a subject of the King of Denmark, whose residence and post-office address is 965 Broadway, Woodcliff, county of Hudson, and State of New Jersey, have invented certain new and useful Improvements in Manufacturing Confectionery, fully described and represented in the following specification, 10 and the accompanying drawings, forming part of the same.

This invention relates to certain improvements in articles of confectionery especially such confectionery as is made in the shape 15 of tablets or disks, which tablets may be assembled in a suitable number into different shapes or configurations, such as bouquets, stars, crosses, etc. Each tablet is enclosed in a suitable wrapper, as paper or tinfoil, 20 and a few different colors of wrapping-material may be employed. Such a collection of tablets made into any chosen grouping or shape, will present not only a very attractive article of sale, but also a very 25 sanitary embodiment of this sort of confection.

The object of the invention is to furnish a protective covering for blocks or pieces 30 of candy, which covering may serve to secure a stem or holder to the block, or tablet, and also to connect a group of such blocks in an attractive design adapted to exhibit the confections in an ornamental combination.

35 These objects are effected by shaping the candy into tablets of such form as to retain a wire upon their surface and provide a projecting stem by which the tablets may be held together in a group of any desired 40 design.

By shaping the tablets as round concaved disks the wire is held securely upon the disk and its projecting ends are twisted together, to retain the tablets in the group 45 selected. The tablets in such case resemble the petals of a large blossom and exhibit the candy in a most attractive form.

The several tablets are secured in the form 50 of the group desired by twisting their respective stems together, and the group presents the appearance of a unitary structure, by fitting a collar to the combined stems; in this manner an imitation of many natural flowers may be effected. All these ornamental effects are based upon the winding of

the wire around the tablet and the twisting of the several wires together to hold the tablets in a group of the desired form.

The parts of the group are thus held together for display and for sale and when 60 bought for consumption the several stems in the group are readily untwisted, and the covering of each tablet unwrapped therefrom. In case the wrapper is applied over the wire coils which encircle the tablets, 65 it is evident that the removal of the wrapper leaves the twisted wire stem attached to the tablet, serving as a handle to support the same while the candy is consumed.

In the said accompanying drawings Figure 1 represents a front view of said improved article of confection in the form of a tablet. Figure 2 is a top view of said tablet showing it bent or incurved. Figure 2^A is a section on line 2—2 in Figure 1. 70 Figure 3 is a vertical transverse section on line X—X of Figure 1. Figure 4 is a perspective view of one oval tablet with the wire wrapped thereon. Figure 5 represents a number of tablets assembled into one arbitrarily chosen configuration, shown here as 75 a bouquet.

Similar characters of references denote 80 corresponding parts throughout the several views.

In Figure 1 A represents a piece of confection preferably made in the shape of a circular tablet or disk having a slight inward curvature as illustrated by B in the top view Figure 2. The body or tablet A is wrapped in paper or tinfoil C to protect it and has wound over and around it a piece of thin wire E as shown in Figure 1; the wire resting upon the bottom of the curve; 90 said wire encircling the body A, may also separately be wrapped in paper or tinfoil of similar quality as that employed in covering the tablet or body A; or the covering with said paper or tinfoil may be effected 95 in different ways, as hereinafter set forth.

One end of said wire is projected from 100 said tablet to form a handle or stem D which may be twisted into different configurations; the other end of said wire is, after being wrapped around said tablet 105 twisted around itself or around its stem as shown at D¹ in Fig. 1, in such a way as to form a compact union with said candy.

This wire or thread may of course be 110 substituted by any semistiff thread-shaped

material; such as celluloid, cane straw and the like without deviating from the principle of this invention; one of the essential features, as said before, being that such 5 piece of confection has a stem or handle connected with it, as described, and permitting the manipulation or arrangement of said candy pieces into one or more chosen designs; as for instance a bouquet as shown 10 in Fig. 5.

The connection of this piece of confection with a wire, or the like, may also be effected as shown in Figure 2^A, by placing the wire directly around and upon the confection where, in case the shape of a tablet is preferred, this tablet has its deepest curvature; and then afterwards covering the tablet and the piece of wire with paper or tinfoil; in this way a secure hold is given 20 to the wire upon the tablet or piece of confection. Still another way to combine the tablet and wire is to cover or roll the tinfoil upon the tablet and fasten the end pieces of the same around that part of the 25 wire or thread that surrounds the tablet and passes over the outwardly curved side, as shown by E in Figure 2^A.

When the wire is thus covered by the tinfoil it forms a ridge along the middle of 30 the tablet, like the vein or rib on a plant which adds to the beauty of the structure materially.

While the curvature on the tablet serves as a seat or resting place for the wire, it 35 also strengthens its hold upon the tablet, besides increasing the beauty of these tablets, when they are assembled into different groups; but it is evident that a flat piece of confection, that is a disk or tablet without 40 curvature would serve a similar purpose.

When the tablets are assembled in a group, the beauty of the whole may sensibly be increased by fitting a paper collar or doily to the handle of the group, as shown

at G in Figure 5. Such a collar not only 45 improves the appearance of the group, but protects the tablets against accidental abrasion.

It will be understood that the covering of 50 this confection is of ornamental character, so as to beautify any group into which it is assembled.

Having thus described my invention, what I claim and desire to secure by Letters Patent is:—

1. The combination, with a group of candy tablets adopted to be assembled to imitate a flower blossom having each a wire wound around its body and its end projected and twisted together, of a handle suited 60 to support the entire group, and formed of the projected ends of all the wires secured together as by twisting and a paper doily fitted to said twisted ends for protecting the tablet against abrasions.

2. An exhibit of confections comprising a group of tablets each having a body of candy, a wire connected thereto, a tinfoil cover for said body and wire to imitate flower petals and leave ribs, said wire having its 70 end extended therefrom and twisted together forming a handle to support the group, and a doily embracing the group to give it a unitary character.

3. An exhibit of confections comprising a group of tablets, each having a body of candy, a wrapper enclosing the same, a wire looped, and extended around each body, with its ends projected from the candy and 75 twisted together, forming a stem to support the tablet, the several stems united together to form a handle for supporting the entire group and a paper doily secured on said stem to protect the confection against abrasions and damage.

In testimony whereof I have hereunto set my hand.

SVENNING DREYER.
